UNITED STATES PATENT OFFICE.

GILBERT LOKEN, OF SEATTLE, WASHINGTON.

SHAKE-SAWING MACHINE.

Application filed June 19, 1926. Serial No. 117,079.

Split cedar shakes form not only a tight roof but are pleasingly rustic and irregular in appearance, and for some types of houses are extremely desirable, either for the roof or on the sides, but as naturally formed they are not readily adapted to modern construction owing to the fact that they are as thick at one end as at the other. Tapered shingles have long been used in roofs and on the sides, but these have always been sawed on both sides and not split, and consequently, having a sawed side outward, their appearance is that of a manufactured article, and they have not the naturally rough appearance inherent in split shakes. Attempts have been made to imitate this naturally rough appearance by scoring the outer faces of sawed shingles from the butt toward the tip, but such scoring, to be done economically, must of course be done by machinery, which produces an appearance of uniformity not consistent with split shakes.

It is my object, then, to produce mechanism whereby tapered shingles can be sawed on one face to leave the naturally split outer face, thus enabling the construction of a house according to modern practice, such as is employed in shingling, yet having the naturally irregular split surface of shakes, presented to the observer.

A further object is the provision of a machine for the purpose intended which will permit the rapid and economical manufacture of such shakes or shingles.

A further object is the production of such a machine which is inherently yieldable or flexible in the sense that it will accommodate the necessary variations in the thickness and curvature of the shakes, yet one which will definitely and exactly determine the thickness of the sawed shake at the tip, where it must fit beneath succeeding courses, and where it should lie flush with adjoining shakes in the same course.

A further object is the provision of such a machine including means for accommodating shakes varying in length or thickness, and yet properly and definitely determining the thickness of the sawed shake at its tip.

A further object is the provision of such a machine which is adapted to power operation.

Other objects, and especially those which relate to structural details, will be apparent from a study of the following specifications:

In the accompanying drawings I have shown my invention in forms which are now preferred by me.

Figure 1 is a plan view of a simple form 60 of my device.

Figure 2 is a section therethrough on the line 2—2 of Figure 1.

Figure 3 is a plan view of a power machine, and 65

Figure 4 is a side elevation thereof.

It will be understood that shakes, usually split from western red cedar logs and split with vertical grain, are fairly uniform in thickness from end to end, and are in general of a fairly plane surface on both sides, except as the various sap rings somewhat break the surface. Occasionally their surface is curved, owing to the proximity of a knot to the split surface. They are frequently split to a thickness of one-half inch or less, but for the purposes of this invention such shakes would ordinarily not be split much thinner than one inch, and might remain thicker. The length of such shakes 80 for the purpose I intend them would be in the neighborhood of two feet or more.

With a thickness of one inch and a length of two feet, and split from the logs as they are, the surface of these shingles would vary 85 somewhat from a true plane at the end farthest from the splitting wedge, and this has been indicated in Figure 2. It is therefore essential that the thin or tip edges of the shingles should be made as nearly as possible

90 the same thickness in order that the necessary irregularities of the outer surface will be minimized as much as possible, and so that the tips of the shingles will lie flush in the same course, and thus will be better adapted 95 to receive the following course and to permit the shingles in the succeeding course to lie close to the shingles below. I have therefore, provided a means for positioning and clamping the shakes upon a carriage, and for 100 carrying the carriage past the saw, the positioning means being so arranged relative to the path of the saw that the thickness of the tip is exactly determined in each instance, and at each end of the shake. In this connection it may be noted that it is immaterial 105

whether the shake is mounted upon a carriage which travels past the saw, or whether the saw is moved through a shake held on a fixed carriage. The former construction is 110 illustrated herein, but it is merely a reversal of this construction to carry the saw through

the shake. It should also be borne in mind that various types of saws may be employed.

As shown herein, a carriage 1 is supported upon a suitable table T, and is guided by the guides 10 for rectilinear movement past a saw. The saw shown herein is band saw S, and as shown in Figures 3 and 4 the band saw is mounted upon the pulleys 9 and 90. The carriage 1 is split as indicated at 11, to receive the saw S, and to insure its rigidity a swinging bar 12, pivoted on one half of the carriage at 13, is engaged by a clamping nut 14 on the other half of the carriage, to secure the two halves rigidly together. Additional positioning pins 15 may be employed for the same purpose. Adjacent one end of the slit 11 a block 2 is located, this preferably being at one side of the slit 11, and being adjustable by means of a clamping pin 20 and nut 21 whereby the block is slidable in a groove 22 paralleling the slit 11. This block engages and positions one end of the shake A and locates it relative to a positioning member which I will now describe.

25 A dog 3 is positioned adjacent each end of the carriage and terminates close to but slightly spaced from the slit 11, whereby it may engage the side face of the shake A and locate its end in conjunction with the block 2 in such a manner that the saw S, as it passes through the shake, will cut the tip ends of uniform thickness. To accommodate variations in the thickness of the shakes, the dogs may be adjustable transversely of the carriage, as by means of the pin and slot connection illustrated at 31. It must be noted, however, that one of this pair of dogs 3 is positioned at one side of the plane of the saw, and the other dog at the opposite side of this plane. In other words, the dogs are spaced longitudinally, and face towards each other to engage opposite faces, at opposite ends of a shake.

The dogs 3 will not alone support a shake, and while the workman might hold the shake, against these dogs 3, yet for safety's sake it is desirable, in order to clamp the shake securely in place, to provide clamping dogs 30, supported upon the carriage and positioned opposite each of the positioning dogs 3. These clamping dogs 30 are pivoted upon the carriage at 32 between their ends, and their outer ends are engaged by links 33, acting through the yieldable springs 34, and the pivot block 35, whereby inequalities in the thickness of the shake can be accommodated and whereby the shake will be firmly yet yieldably gripped and held on the carriage, inclined slightly relative to the general plane of the saw to cut the shake into two tapered shingles.

The two links 33, running to the respective clamping dogs 30, preferably are connected to a common lever 4 at a point 40 outward of the fulcrum 41 of the lever. The

lever is provided at its opposite end with a handle 42, and the connection of the links 33 to the dogs 30 is so arranged that by pushing on the handle 42 the dogs 30 are caused to cooperate with the dogs 3 to clamp a shake between them; thus the handle 42 may be engaged and pushed forward to clamp a shake after it has been positioned between the pairs of dogs, and the same movement urges the carriage forward toward the saw S and tends to clamp the shake securely during the sawing operation. A handle 16 may be provided directly on the carriage 1, whereby the lever 4 may be relieved of undue strain.

The machine thus far described is intended wholly for hand operation and has been found to work very satisfactorily. It may be desirable however, to provide feed means for the shakes, to provide power means for advancing the carriage, or to provide power means for removing the sawed shakes. In Figures 3 and 4 I have shown power means for advancing the carriage and for removing the sawed shakes, and while no feed mechanism other than hand feed has been illustrated, it will be evident that a suitable feed mechanism might be devised.

The device shown in Figures 3 and 4 is in all essential respects like that shown in Figures 1 and 2. The end of the lever 4 is provided with an extension 43, and to this extension is connected a pitman 44 connected to a crank disc 54. This crank disc is driven from a power shaft 5, in turn driven by a motor M through suitable gearing 58 and a clutch 52, operable through a clutch pedal or lever 51. The operator, by stepping upon or releasing the pedal 51 to its return spring 50, may cause engagement or disengagement of the clutch members 52, and in this way controls the advance or retraction of the carriage 1.

To remove the sawed shakes I may provide friction rollers 6 arranged in pairs in the path of movement of the shake, and continuously driven, as by belts 60 running over the rollers 6 and live rollers 61, these latter in turn being driven from vertical shafts 62 driven from the shaft 5 by gearing 56. The rollers 6 and 61 are mounted upon swinging arms 63 and are yieldingly held in the path of the sawed shake, as by means of springs 64; thus as the shake passes the saw S it engages and forces aside the rollers 6, which, rotating continuously in a direction tending to move the shake away from the saw, will cause such movement of the shake as soon as it is released from the clamping dogs 30. Such release occurs as soon as the carriage 1 has completed its advance and the pitman 44 has moved the lever 4 rearward. Such rollers 6 may be employed even though the carriage is advanced by hand.

To complete the delivery of the shakes, they may be dropped from the rollers 6 upon live rolls 7 driven, as by a belt 70, from the power shaft 5, and by such a conveyor or any other suitable means, may be delivered to a point where they may be packed or otherwise handled.

What I claim as my invention is:

1. A shake sawing machine comprising, in combination with a saw, a carriage movable past the saw, means including a member at each end of the carriage and at opposite sides of the plane of the saw, and spaced a predetermined distance from the plane of the saw, for positioning a shake upon the carriage in a position generally within the plane of the saw but inclined slightly relative thereto. 70
2. A shake sawing machine comprising, in combination with a saw, a pair of means for positioning the opposite faces of opposite ends of a shake a predetermined distance from the plane of the saw, the two members of said pair being located at opposite sides of such plane, and means co-operating with said positioning means for holding said shake in engagement therewith. 75
3. A shake sawing machine comprising, in combination a saw, guides paralleling the plane of the saw, a carriage slideable along said guides, a positioning means projecting upwardly from said carriage at each end, and located at opposite sides of the plane of the saw, said means being adapted to engage opposite faces of a shake to position it generally within but inclined slightly relative to the plane of the saw, and means cooperating with said positioning means to clamp said shake upon the carriage. 80
4. A shake sawing machine comprising, in combination a saw, guides paralleling the plane of the saw, a carriage slideable along said guides, two positioning means projecting upwardly from said carriage and spaced longitudinally thereof, and located at opposite sides of the plane of the saw, said means being adapted to engage opposite faces at opposite ends of a shake to position it generally within but inclined slightly relative to the plane of the saw, means cooperating with said positioning means to clamp said shake upon the carriage, and an end stop engageable with the end of a shake, and cooperating with said positioning means to determine the thickness of the tip of the sawed shingle. 85
5. A shake sawing machine comprising, in combination with a saw, a pair of means for positioning the opposite faces of opposite ends of a shake a predetermined distance from the plane of the saw, the two members of said pair being located at opposite sides of such plane, and yieldable clamping means engageable with the side faces of said shake opposite each of said positioning means, and co-operating therewith to position said shake. 90
6. A shake sawing machine comprising, in combination with a saw, a pair of normally fixed means for positioning the opposite faces of opposite ends of a shake a predetermined distance from the plane of the saw, the two members of said pair being located at opposite sides of such plane, means co-operating with said positioning means for clamping said shake in position in engagement with the latter, and means permitting adjustment of said positioning means towards or from the plane of the saw. 95
7. A shake sawing machine comprising, in combination with a saw and a carriage movable therewith, a pair of means for positioning the opposite faces of opposite ends of a shake a predetermined distance from the plane of the saw, the two members of said pair being located at opposite sides of and spaced longitudinally of such plane, means for clamping said shake upon the carriage in engagement with said positioning means, and means operable to advance said carriage toward the saw and to move said clamping means into operative position, and adapted to release said clamping means as the carriage reverses its movement. 100
8. A shake sawing machine comprising, in combination with a saw and a carriage movable therewith, a pair of means on the carriage for positioning the opposite faces of opposite ends of a shake a predetermined distance from the plane of the saw, the two members of said pair being located at opposite sides of such plane, means for clamping said shake upon the carriage in engagement with said positioning means, means operable to advance said carriage toward the saw and to move said clamping means into operative position, and adapted to release said clamping means as the carriage reverses its movement, and means engageable with the sawed shake after it has passed the saw, and operable upon release of said clamping means to remove and advance the sawed shingles. 105
9. A shake sawing machine comprising, in combination, a saw, guides paralleling the plane of the saw, a carriage slideable along said guides, means for positioning and clamping a shake on edge upon said carriage in the plane of said saw but inclined slightly to produce a diagonal cut as the carriage advances, said means including a positioning dog engaging a side face and a clamping dog engaging the opposite side face at each end, a link extending from each clamping dog, and a power connection to the said links, whereby the shake is clamped as the carriage advances towards and past the saw, and is released as the carriage is retracted. 110
10. A shake sawing machine comprising, in combination a saw, guides paralleling the plane of the saw, a carriage slideable along said guides, means for positioning and clamping a shake on edge upon said carriage 115

in the plane of said saw but inclined slightly to produce a diagonal cut as the carriage advances, said means including a positioning dog engaging a side face and a clamping dog 5 engaging the opposite side face at each end, a link extending from each clamping dog, and a power connection to the said links, whereby the shake is clamped as the carriage advances

towards and past the saw, and is released as the carriage is retracted, and a pair of live 10 rollers yieldably urged together and positioned to engage opposite side faces of the shake behind the saw.

Signed at Seattle, King County, Washington, this 11th day of June 1926.

GILBERT LOKEN.
